To all whom it may concern:

Be it known that I, Carolyn Le Sac, a citizen of the United States, residing at Milwaukee, Wisconsin, in the county of Milwaukee and State of Wisconsin, have invented a new, original, and ornamental Design for a Lady's Handbag, of which the following is a specification, reference being had to the accompanying drawing, forming part thereof.

In the drawing:

Fig. 1 is a plan view of a lady's handbag in unfolded condition, the back being plain;

Fig. 2 is an edge view of the lady's handbag in the condition of Fig. 1;

Fig. 3 is a plan view in doubled-over condition; and

Fig. 4 is an edge view of the lady's handbag in the condition of Fig. 3.

I claim:

The ornamental design for a lady's handbag, substantially as shown and described.
